METHOD FOR CLEANING ARTICLES OF
CLOTHING AND THE LIKE

Louis Angelus, New York, and Daniel Lawrence Baylis, Long Island, N. Y.; said Baylis assignor to said Angelus

Application October 16, 1933, Serial No. 693,758

1 Claim. (Cl. 68—38)

Our present invention relates generally to the cleaning art, and has particular reference to an improved method for cleaning such things as articles of clothing or the like.

5 The type of cleaning method to which our invention is primarily directed is of the character which effects a so-called "dry cleaning", customarily accomplished by subjecting the articles to be cleaned to a suitable chemical cleaning fluid.

10 Before proceeding to describe the features of our present invention, we will state that in the practice of the dry cleaning art it is customary to provide a work chamber or casing which is adapted to contain a mass or body of the selected 15 cleaning fluid and into which the articles to be cleaned may be placed so as to be subjected to the action of such fluid. Usually, the casing or shell is constructed to accommodate a body 20 of the cleaning fluid in the lower part thereof, and it is provided with apparatus and parts for permitting the articles to be immersed into the body of fluid, subjected to agitation, withdrawn from the fluid, and finally dried by centrifugal 25 action.

More particularly, the general type of apparatus to which reference has been made includes a basket or container which is mounted for rotation around a vertical axis, and also for 30 vertical reciprocation along the axis. The main driving is usually, though not necessarily, provided by means of a suitable electric motor or the like, and the movements of the basket are generally accomplished by suitable mechanism 35 which includes a plunger constructed and arranged to permit of vertical reciprocation there- 40 of for agitation purposes, and to permit of a rotation thereof when the basket is to be subjected to rotation. Means are usually provided for disconnecting the plunger from the basket at desired intervals, as will be more fully explained hereinafter.

It is a general object of our invention to provide an improved method whereby articles may 45 be more satisfactorily and more efficiently cleaned, the method being preferably carried out by means of an apparatus of the foregoing character.

The advantages of our present improved 50 method will be more fully appreciated when it is borne in mind that the cleaning fluid to which the articles are subjected necessarily dissolves and withdraws unto itself a large quantity of dirt and impurities. Attempts have heretofore 55 been made to divest the fluid of these impurities

by means of a circulatory system which includes a filtering device. In a large measure, a filtering system of this general character is satisfactory and it maintains the fluid in substantially purified condition.

5 A factor which has heretofore been overlooked, however, lies in the tendency of impurities to seek the surface of the body of fluid in the casing and to float upon this surface. Accordingly, while the main body of cleaning fluid may 10 be substantially pure by virtue of the filtering action, unsatisfactory cleaning has nevertheless been all too frequently effected. We have discovered that, to a large extent, the unsatisfactory results heretofore encountered are due to 15 the impurities which the ordinary circulatory system does not affect, and which are permitted to remain in a floating condition upon the surface of the body of fluid. We have found that the general mode of operation of cleaning devices of this sort results in imparting to even 20 small amounts of these floating impurities a unique and unusually potent ability to impair the efficiency with which the articles are cleaned. In other words, it is the up-and-down movement 25 of the articles into and out of the cleaning fluid which gives even small quantities of floating impurities a remarkable and highly undesirable opportunity to work their way into the fibers of the articles.

30 Our present invention has particular reference to an improved method whereby the foregoing causes of many unfavorable results, heretofore frequently encountered, are effectively counteracted.

35 Our improved method provides for an effective and novel type of rinsing action as and when the articles are withdrawn from the main cleaning fluid, any floating dirt and dust particles thus being left in the main body of fluid in the 40 body of the chamber.

Briefly, our invention resides in a new and improved method of subjecting articles to a cleaning fluid, whereby the articles are initially submersed into a main body of fluid; then subjected to the rinsing action of clean filtered fluid out of contact with the main body of fluid; and finally dried by centrifugal means; all of 45 these procedural steps being preferably accomplished coincidentally with a continuous circulation of the fluid in a single circulatory system, whereby the washing and the rinsing action are obtained from a single original quantity of fluid.

We achieve the foregoing objects, and such other objects as may hereinafter appear or be 50

pointed out, in the manner illustratively exemplified in the accompanying drawing, wherein—

Figure 1 is an elevational side view of a simple form of apparatus with which our present invention may be practiced;

Figure 2 is a diagrammatic view showing the relationship of parts during the main washing operation;

Figure 3 is a view similar to Figure 2, illustrating the rinsing effect of our present method;

Figure 4 is a view similar to Figure 3, during the extracting or drying procedure; and

Figure 5 is a view similar to Figures 2, 3, and 4, illustrating a slightly modified arrangement.

While much of the driving and control mechanism, which forms no part of our present invention, has been omitted from the drawing, its general arrangement and mode of operation will be clear to those skilled in the art from the general illustrations contained herein and from the description hereinafter to be given.

In Figure 1, we have shown a cylindrical casing or work chamber or shell 10 which is mounted in a suitable manner in a substantially vertical position. This shell is usually provided with a hinged cover 11 to permit access to the interior thereof when the articles are placed into the casing or withdrawn therefrom. An electric lamp 12 is preferably mounted in association with the top wall of the casing, and in combination with a window of suitable character to permit the interior of the casing to be under the constant supervision of the operator while it is operated.

The apparatus includes a filtering device which we have illustrated generally by the reference numeral 13 and which may be of any suitable character. A conduit 14 communicates with the fluid in the lower portion of the casing 10 and is adapted to lead the fluid to a circulating pump 15 from which the fluid enters the filter 13. From the latter, the fluid passes preferably through a precooler 16, and thence through an inlet conduit 17, and back to the casing 10. Valves 18 and 19 are preferably arranged in association with the conduits 14 and 17.

The inlet conduit 17 communicates with the casing 10 at an upper portion thereof, or, at least, at a portion which permits the articles in the casing 10 to be subjected to the filtered fluid from the conduit 17 during and after the main washing operation.

In Figures 2, 3, and 4, we have diagrammatically indicated the arrangement and mode of operation of the interior parts of the apparatus. The basket 20 is usually provided with perforations or holes, and is mounted upon an axis 21 which is substantially coincident with the axis of the casing 10. The basket 20 is adapted to be shifted or adjusted in a vertical manner from substantially the position shown in Figure 2 to substantially the raised or withdrawn position shown in Figures 3 and 4. This raising and lowering of the basket 20 may be accomplished by any suitable mechanism, and is usually controlled by a foot pedal 22 or the like. By referring to Figures 2, 3, and 4, it will be noted that the basket 20 is adapted to be shifted or adjusted to selectively lower it into the main body of fluid 23 or to raise it above the level of said fluid, as indicated in Figures 3 and 4. Under certain circumstances, it may be desirable to lower the level of the body of fluid 23 during the time that the basket 20 is raised into its withdrawn position. This may be accomplished by

withdrawing some of the fluid into a reserve tank or into another cleaning vessel associated with the same filter 13.

Coaxially mounted with respect to the basket 20 is a plunger 24 adapted to be set into reciprocation between the raised full-line position of Figure 2 and the lower dot-and-dash position, whenever an agitating action is desired. This oscillating or reciprocation of the plunger 24 may be accomplished by any suitable mechanism, usually by means of an electric motor and such other apparatus as may be necessary to convert the rotative movement of the motor into reciprocating movements.

A rotative movement of the plunger is preferably provided for, also, where the plunger itself is to serve as the medium through which the basket 20 is rotated. Where such an arrangement is used, suitable means is provided for connecting and disconnecting the plunger 20 from the basket 20. For example, the exteriorly accessible handle 25 may be used for adjusting or loosening the screw or similar device in the interior of the casing for effecting a connection or disconnection of the plunger from the basket 20.

In accordance with our present invention, the inlet conduit 17 communicates with the interior of the casing 10 at a point and in a manner adapted to subject the articles in the basket 20 to the action of the filtered fluid when the basket 20 is in the raised or withdrawn position of Figures 3 and 4. More particularly, we provide a construction whereby the inlet conduit 17 terminates in a spraying device arranged above the level of the raised basket 20. We have illustratively shown a circular perforated pipe or conduit 26 mounted circumferentially along the inner wall of the casing 10 and adapted to direct a spray of fluid 27 downwardly, as indicated.

When the present device is operated, the basket 20 is first raised; the cover 11 is opened; and the articles to be cleaned are placed into the basket 20. The cover 11 is then closed, and the basket is lowered into submersed position with respect to the body of fluid 23. The plunger 24 is then preferably set into operation to reciprocate vertically and thereby agitate the articles in the basket 20 and subject them thoroughly to the action of the fluid in which they are immersed. During this washing procedure, the circulatory system is continuously operated, whereby fluid is drawn from the body 23, through the pump 15, to the filter 13, and thence back into the casing through the conduit 17 and the spraying device 26. The action of this spray upon the articles during their immersion into the body 13, and during the agitative washing procedure, is to prevent any impurities from the surface of the body of the fluid 13 from entering into or adhering to the articles in the basket.

After a predetermined period of time, the reciprocation of the plunger 24 is discontinued, and the basket and plunger are raised into the position of Figures 3 and 4. The circulatory system continues to operate, and during the raising of the basket no impurities from the surface of the fluid are permitted to adhere to the cleaned garments. In fact, any impurities that may be raised with the basket 20 or with the articles therein are immediately and effectively washed out by the spraying action.

The plunger 24 may then be connected to the basket 20 and set into rotation, whereby the ar- 75

ticles in the basket 20 are thoroughly and effectively subjected to a rinsing action with filtered fluid.

After a predetermined rinsing procedure, the circulatory system is discontinued, but the rotation of the basket 20 is continued, as indicated in Figure 4, as a result of which the articles in the basket 20 are subjected to a thorough centrifugal action which throws off excess fluid and renders them substantially dry. The rotation during this extracting procedure is preferably conducted at a substantially greater speed than during the rinsing procedure of Figure 3.

Finally, the articles are withdrawn from the basket 20 and they will be found to have been subjected to a thorough and highly efficient cleaning action, ready for final treatment.

In Figure 5, we have shown an arrangement whereby the basket 28 may be caused to rotate during the rinsing procedure independently of any driving action from the plunger or from any other driving member. In fact, in Figure 5, we have shown the possibility of permitting the returning filtering fluid to serve the dual function of spraying the articles and also rotating the basket 28. In Figure 5, the inlet conduit 29 is provided with the branch 30 terminating in the spraying device 31 and with the branch 32 terminating in the nozzle 33. The latter is adapted to direct a stream of fluid against a series of suitably constructed vanes 34 provided in association with the basket 28 and adapted to cause rotation of the basket 28. Although we have shown the driving stream directed against exteriorly arranged vanes 34, nevertheless such a driving action may be accomplished in association with vanes arranged on the interior of the basket 28. Under certain circumstances, the spray 35 may itself be of a character suitable for causing a rotation of the basket 28.

The conduit 30 is provided with a valve 36 to

permit the spray to be discontinued while still continuing the rotative effect of the stream from the nozzle 33.

Although we have shown only one casing 10 in association with the filter 13, we have found it satisfactory to carry out our present invention in a duplex type of apparatus wherein two work casings are connected in parallel to the filter 13. In such an event, it is most satisfactory to use the casings successively, although, under certain circumstances, they may, if desired, be used simultaneously. The successive mode of operation of two casings permits the single original quantity of fluid to be utilized to advantage in one of the casings, while the other one is adjusted for the extracting operation indicated in Figure 4. Also, one of the casings may be emptied and refilled without impairing or interfering with the continued action of the cleaning fluid on the articles in the other casing.

In general, it will be obvious that changes in the details herein described and illustrated for the purpose of explaining the nature of our invention may be made by those skilled in the art, without departing from the spirit and scope of the invention as expressed in the appended claim. It is, therefore, intended that these details be interpreted as illustrative, and not in a limiting sense.

Having thus described our invention, and illustrated its use, what we claim as new and desire to secure by Letters Patent is—

In a dry cleaning process, the steps of submerging the articles to be cleaned in a bath of dry cleaning solvent, spraying clean solvent continuously on the surface of the bath, agitating the articles in the bath, and lifting the articles out of the bath into the spray while the surface of the bath is being sprayed.
